UNITED STATES PATENT OFFICE.

EMILE J. LUSTER, OF NORRISTOWN, PENNSYLVANIA, ASSIGNOR TO THE LUSTER-JORDAN COMPANY, INCORPORATED, OF NORRISTOWN, PENNSYLVANIA, A CORPORATION OF PENNSYLVANIA.

AUTOMATIC PROFILING-MACHINE.

1,306,266.

Specification of Letters Patent. Patented June 10, 1919.

Application filed September 5, 1917. Serial No. 189,789.

To all whom it may concern:

Be it known that I, EMILE J. LUSTER, a citizen of the United States, residing at Norristown, in the county of Montgomery and State of Pennsylvania, have invented 5 a certain new and useful Improved Automatic Profiling-Machine, of which the following is a specification.

Generally stated the invention relates to 10 apparatus for machining regular and irregular surfaces of various articles both internally and externally considered and more particularly has reference to a machine for making, blanking and trimming dies, 15 punches, and the like.

As at present commonly practised, the contour, shape or form of a die or punch is laid out by hand and then finished upon machines of various types in which more 20 or less handwork or adjustment is necessary, which considering the amount of time consumed in the operation and the requirement for a skilled workman is an expensive mode of procedure.

25 The principal object of the present invention is to overcome these disadvantageous features and provide a profiling machine, the parts of which are correlated with respect to a vertically reciprocal cutting tool 30 whereby by the employment of a templet, a table containing work is so operated that the work is fed toward the tool irrespective of any irregularity of contour of the templet design. A further object of the present invention is to automatically arrest lateral 35 movement of the table during a cutting stroke of the tool and to advance the table toward the tool upon a return stroke thereof.

40 A further object of the present invention is to provide a table for supporting work in which superimposed parts are present capable of varied movements one with respect to the other for effecting lateral, tilt-able and concentric and eccentric rotative 45 movement with respect to a cutting tool. A further object of the present invention is to provide a cutting tool so disposed that it may be rotated around its vertical axis. A further object of the present invention 50 is to provide a cutting tool the cutting edge of which may be either parallel or inclined with respect to the guiding face of the tool which cutting edge may be either an integral part of the tool or an insert. A still

further object of the present invention is 55 to provide a clutch controlled train of gear wheels operatively connected with a ram for reciprocating the cutting tool, which clutch is automatically shiftable for operating a selective group of gear wheels for reversal of the ram. Other and further objects of the present invention reside in the provision of certain new and novel arrangements, connections and combinations of parts as will be hereinafter more specifically referred to.

The invention consists of the improvements hereinafter described and finally claimed.

The nature, characteristic features and 70 scope of the invention will be more fully understood from the following description taken in connection with the accompanying drawings forming part hereof and in which:

Figure 1 is a view in side elevation of the 75 machine embodying features of the invention.

Fig. 2 is a front view thereof.

Fig. 3 is a view in cross-section taken upon the line 3-3 of Fig. 1.

Fig. 4 is a fragmentary view upon an enlarged scale of the lower portion of Fig. 1.

Fig. 5 is a top or plan view of the table of the machine, viewed from the front.

Fig. 6 is a face view of Fig. 5, partly sectioned.

Figs. 7 and 8 are fragmentary views in plan and elevation respectively of a device for tilting the work table.

Figs. 9 and 10 are fragmentary views 90 illustrating a templet above and below work, respectively.

Fig. 11 is a view in elevation of a cutting tool provided with means for moving the same around its vertical axis.

Figs. 12 to 17 inclusive are elevational views illustrating various types of tools as may be employed.

Figs. 18 to 23 inclusive are views in cross-section of the tools shown in Figs. 12 to 17, 100 and.

Figs. 24 to 28 illustrate work as effected by the present machine and hereinafter more particularly referred to.

For the purpose of illustrating my invention, I have shown in the accompanying drawings one form thereof which is at present preferred by me, since the same has

been found in practice to give satisfactory and reliable results, although it is to be understood that the various instrumentalities of which my invention consists can be variously arranged and organized and that my invention is not limited to the precise arrangement and organization of the instrumentalities as herein shown and described.

Generally stated, the machine is made up 10 of a supporting casing or shell of substantially rectangular configuration located upon the top of which is a work receiving table, vertically reciprocal through which is a cutting tool. A ram is positioned at the 15 front of the machine for reciprocating the tool, the ram being operated from the interior of the casing. The limit of the up and down strokes of the ram are determined by a device at one side of the machine which 20 connects between the ram and the operating means. Upon the same side of the machine are other connections for effecting intermittent rotation of certain parts of the table and upon the opposite side of the 25 machine and connected between the ram and the table is a device for locking the table against lateral movement during the cutting stroke of the tool. A detailed description will now be given of these parts.

30 *Main operating mechanism.*—At the base of the machine is journaled a two-part main driving shaft 1 provided with a cone-pulley 1' for driving purposes. Mounted upon one part of shaft 1 is pinion 2 fixed to which is 35 a friction-disk 2' and mounted upon the other part of shaft 1 is a pinion 3 fixed to which is a friction-disk 3', a friction clutch 4 being present for engaging one or the other of said friction-disks, which clutch is 40 automatically operated by a device to be presently described. Paralleling the main shaft is a rock-shaft 5 mounted upon which is a gear-wheel 5' which is in mesh with the pinion 2. Also mounted upon shaft 5 45 is a gear-wheel 5'' which is in mesh with a reversing gear wheel 5''' which in turn is in mesh with pinion 3. Also paralleling shaft 2 is a shaft 6 upon which are mounted pinions 6' and 6'' and a gear-wheel 6'''.

50 The pinions 6' and 6'' are in mesh with the gear wheels 5' and 5'' respectively and the gear wheel 6''' is in mesh with the rack-bar 7 of the ram 7', see Fig. 2.

55 *Ram.*—The ram 7' is vertically slidable upon the front of machine between lugs 7'' and retained in proper position as by plates 7''' secured to the machine casing. The rear of the ram is counter-sunk to receive the rack-bar 7 which is fixed thereto.

60 Clamped to the front face of the ram are stops 8 of which there are two. These stops are adapted in the upward and downward movement of the ram to coöperate with a lever 9 extended across the front of the 65 machine, the free end of which lies in the

path of travel of said stops, see Fig. 2. This lever has fixed relation as at 9' with a shaft 9'', suitably journaled upon one side of the machine, see Figs. 1, 3 and 4 adapted to have imparted thereto a rocking motion in the operation of the ram. 70

75 *Clutch shifter.*—The shaft 9'' is provided with suitable means for shifting the friction clutch 4. Suitably connected with the friction clutch 4 is an endwise shiftable rod 10 which passes through one end of the two part driving shaft 1, see Fig. 3, and projects beyond the detachable plate 11. Engaging the projected end of the rod 10 is the forked end 12' of a tappet arm 12 80 fixed upon the shaft 9'' suitable means being present upon the rod 10 as a collar and nut to maintain correlation between the rod and tappet arm. The free end of the tappet arm is balanced in its operation by means 85 of a spring pressed plunger 13. Thus in the operation of the ram, the rod 10, through the above described connections, shifts the friction clutch 4 into engagement with the friction disk 2' to move the ram upward 90 and into engagement with the friction disk 3' to move the ram downward. The ram is provided at its top with a cutting tool 14 which has reciprocal movement through a work supporting table 15. 95

100 *Work table.*—The work table 15 primarily is made up of five superimposed parts or units, each capable of different movement with respect to another part. The lowermost part is designated 15^a, has lateral sliding movement through ways 15^c upon the top of the machine casing and has a counter-balanced connection 15^b, whereby the said part has the tendency to always move toward the cutting tool. Mounted 105 upon the slidable part 15^a is a tiltable part 15^d hinged thereto as at 15^e. This part together with the parts superimposed thereon may be inclined with respect to the part 15^a by adjustment of screw 16, see Figs. 5, 7 and 110 8. In said figures, it will be noted that the part 15^a is provided with a lug 16' having a beveled face over which may be caused to ride adjusting the screw 16, a notched member 16'', whereby the tiltable part may be inclined to suit work requiring a taper. Rotatably mounted within the part 15^d is a worm gear wheel 17, see Fig. 6, fixed to which is a table part 17' which bears upon the top of the tiltable table part. In mesh 115 with the worm gear wheel 17 is a worm 17'' mounted upon a shaft 17''. Fixed to this shaft is a ratchet wheel 18 to which motion is imparted by mechanism to be presently described for imparting an intermittent, rotary movement to the table part 17'. Upon the top of table part 17' is another rotatable table part 19 provided therebeneath with a ring 19' upon which the table part is guided, guiding lugs 19'' being present for this pur- 120 125 130

pose of which one may be adjustable in order to take up wear. The parts 19—19' are clamped to lateral projections 20 upon the tiltable part 15^a as by adjustable lugs 20'. 5 Thus the ring and its table parts may be adjusted to travel concentrically or eccentrically with respect to the table part 15^a which has a true circular movement. Carried by the ring is a tooth annulus 21 with 10 teeth top and bottom. This annulus is so mounted that it may be rotated around the ring 19', the purpose of which will presently appear. The uppermost table part 22 is mounted upon the table part 19 and may be 15 shifted in a direction transversely of the movement of the lowermost table part. This movement as well as other of the table movements are effected by mechanism connected with the shaft 5 at the machine base, a description of which will now be given. 20

Table operating mechanism.—Fixed to the shaft 5 which in operation has a rocking or semi-circular movement, is a slotted disk 23, see Fig. 4, adjustably mounted in the slot of 25 which is a member 24 secured to which is an operating rod 25. The rod 25 at its opposite end is connected with a pawling device 26 loosely mounted upon the shaft 17'', see Fig. 5. Upon said shaft is fixed the ratchet 30 wheel 18 which in the pawling movement of said connections imparts an intermittent movement to the shaft 17''. Fixed to stud-shaft 27 is a pinion 28 which is in mesh with the teeth upon the underside of the 35 annulus 19, thereby imparting intermittent movement to the annulus. In mesh with the teeth upon the top of the annulus is a pinion 29 mounted for engagement or disengagement by means of a clutch 30 with the ratchet wheel 31 which is fixed to a screw-shaft 32 co-operatively engaging with the 40 slideable table part 22. Connecting a pawling device 33 which pawls the ratchet wheel 31 is a rod 34, see Fig. 1, whereby the two 45 ratchet wheels may be driven in unison or by disconnecting rod 25 ratchet wheel 18 may be driven alone. Likewise rotary motion along with table part 19 may be had by the proper shifting of clutch 30 or not 50 as desired. Thus arranged, these particular parts may be operated by hand when desirable. In the operation of the table parts, it is desirable to lock a lowermost section or unit during a cutting stroke of a tool and 55 a description will now be given of such device.

Table lock.—Mounted upon the ram 7' by means of a yielding connection 35 is a brake-shoe 36, see Fig. 3. Connecting with the 60 brake-shoe as at 37 is a brake-lever 38 pivoted as at 39 to a lug 40 upon the machine casing. The free end of this lever 38 is provided with a pin 41 for engaging an aperture in the lowermost table part 15^a 65 upon the cutting stroke of the tool 14 and

to be withdrawn therefrom upon the return stroke of the tool to permit the counter-weight connection 15^b to draw the table as a whole toward the cutting tool, a description of which will now be given. 70

Cutting tool.—It is desirable in some instances that the cutting tool 14 be so positioned that it may be manually moved around its vertical axis and a description will be given of such a connection, reference 75 being had to Fig. 11. The ram top is provided with a tool clamp 42, which receives a tool shank 43 which in turn receives the tool 14, a nut 44 being present to secure the tool in position. A nut 45 is present for 80 engaging with the tool clamp to lock the tool shank to place. The tool is provided at the upper end with a keyway 46 and projects through a bushing 47 having a key which bushing is supported by the arm 48 85 which is adjustable as at 49 upon a standard 50 of the machine. By loosening nut 45, the tool may be turned a proper distance by means of bushing 47. The tools employed may be of varied design and in Figs. 12 to 90 23, I have illustrated several forms thereof. The recessed portion 50 may be either parallel to the guiding face 51 as shown in Figs. 12, 13, 14 and 17 or inclined to the guiding face as in Fig. 15. The cutting edge 95 52 may be an integral part of the tool or an insert as at 53 in Fig. 16 and may be either at right angles to the guiding faces or at an inclination thereto. The tool may operate upon its downward stroke as shown 100 in Fig. 9 or upon its upward stroke in Fig. 10. In Fig. 9, the templet 54 is above the work 55 and the tool is guided by the bushing 47. In Fig. 10, the templet 54 is below the work and guides the tool. In such case, 105 the tool need not be guided through the arm 48. A description will now be given of the operation of the machine.

Operation.—The work 55 and templet 54 are clamped upon the uppermost table part 110 by clamps 56 and a suitable tool 14 selected and properly positioned. In this connection, it is to be observed that all of the table parts are centrally apertured as shown clearly in Figs. 5 and 6. The tool is so 115 adjusted that its cutting edge does not come above or beyond the space between the templet and the work, see Fig. 9. Should it be desired to cut circular work, for instance as shown in Fig. 24, the machine 120 parts are adjusted so that with the exception of the table parts 15^a and 15^a the other table parts are in neutral positions. If it be desired to cut oval work as designated in Fig. 25, the lugs 20' are adjusted out of center 125 to desired distance in order that table part 19 shall have imparted thereto an eccentric movement, the lower table part still describing a true circle so that combined an oval may be described. Should it be desired to 30

have the top table part have a transverse movement coincident with the oval movement to produce a cut as shown in Fig. 26, then the ratchet wheel 31 and clutch 30 are thrown in action. A cut as shown in Fig. 27 is effected by operating the table having a true circular movement in conjunction with the table part having a transverse movement. If it be desired to cut as designated in Fig. 28, the top table is operated in a straight transverse manner only. It will thus be seen that it is possible to use the work table for true circular or oval work for only a part of the table movement after which it is possible to use a transverse feed. It is thought the operation of cutting beveled work by tilting of the hinged table will be understood without further description.

It will now be apparent that I have devised a novel and useful construction which embodies the features of advantage enumerated as desirable in the statement of the invention and the above description, and while I have in the present instance shown and described the preferred embodiment thereof which has been found in practice to give satisfactory and reliable results, it is to be understood that the same is susceptible of modification in various particulars without departing from the spirit or scope of the invention as defined in the appended claims or sacrificing any of its advantages.

What I claim is:

1. A machine of the character stated embracing a vertically reciprocal tool, a medium for operating the tool, an endwise movable table through which the tool operates, means for selectively rotating one portion of said table with respect to another portion in concentric and eccentric relation, means for moving a portion of the table transversely with respect to the endwise movable portion, means between said tool operating medium and the endwise movable portion of the table to arrest endwise movement thereof during a cutting stroke of the tool and independent means for advancing the table toward the tool upon the return movement of the tool.

2. A machine of the character stated embracing a vertically reciprocal tool, a ram for operating the tool, a table through which said tool operates which table consists of superimposed parts capable of endwise, tiltable, rotatable and transverse movement, means between said ram and the endwise movable portion of the table for arresting endwise movement thereof during a cutting stroke of the tool, independent means for advancing said endwise movable portion of the table toward the tool upon the return stroke thereof, means for tilting the tilttable portion of the table, means for rotating the rotatable parts of the table in concentric

relation, means for effecting a rotation of 65 said rotatable parts in eccentric relation and means for moving a portion of the table transversely with respect to the endwise movable portion of the table.

3. A machine of the character stated comprising a vertically reciprocal tool, a ram provided with a tool clamp for rotatably supporting the tool, means connected with the tool for rotating the same around its vertical axis, an endwise movable table through 75 which the tool operates, means for selectively rotating one portion of said table with respect to another portion in concentric and eccentric relation, means for moving a portion of the table transversely with respect to the endwise movable portion, means between 80 said tool operating medium and the endwise movable portion of the table to arrest endwise movement thereof during a cutting stroke of the tool and independent 85 means for advancing the table toward the tool and upon the return movement of the tool.

4. A machine of the character stated comprising a vertically reciprocal tool, a medium 90 for operating the tool, superimposed table parts capable of varied adjustments movable in unison laterally of the machine one of said table parts being capable of a movement transversely of said lateral movement, means 95 for feeding the last mentioned table part transversely, means for disengaging said feed, a braking device for arresting slideable movement of the table parts during a cutting stroke of the tool and positive means for advancing the table parts toward the tool during 100 its return stroke.

5. In a machine of the character stated, a slideable table part, a tilttable table part, a worm gear, a worm, a cable part fixed to the 105 worm gear for rotatable movement upon the tilttable table part, means for intermittently driving said worm, a table part capable of eccentric movement mountable upon and rotative with said rotatable table part, a transversely movable table part mounted upon the table part having an eccentric movement, means for imparting a transverse movement to such table in conjunction with said worm feed and means for imparting a transverse 115 movement to such table independently of the worm feed.

6. In a machine of the character stated a slideable table part, a tilttable table part, a worm gear, a worm means for intermittently 120 driving said worm, a rotatable table part fixed to said worm gear for rotatable movement upon said tilttable table part, a table part capable of an eccentric movement mounted upon the rotatable table part, a 125 toothed annulus rotatably carried by the table part having an eccentric movement and a ratchet wheel connection for driving

said annulus independently of the operation of said worm.

7. A machine as described in claim 6 having a transversely movable table mounted 5 upon the table having an eccentric movement, a screw-thread feed for moving said table transversely, a pinion for the feed screw which is in mesh with said annulus and a clutch for shifting said pinion to dis- 10 engage the feed screw.

8. In a machine of the character described, a reciprocal tool having a substantially horizontal cutting edge and a guiding face and a recessed portion substantially at right 15 angles thereto, a ram for operating the tool, a table capable of varied movements including lateral movement through which the tool works, means for operating the ram, a brake shoe and a brake lever under spring tension 20 connected with respect to said ram for arresting lateral movement of the table during a cutting stroke of the tool and means for advancing the table toward the guiding face of the tool during its return stroke.

25 9. In a machine of the character stated, a

laterally movable table part, a second table part tiltably mounted thereon, a beveled lug, a movable bar for riding over said lug to tilt the table and a screw engaging said bar to move the bar with respect to the lug. 30

10. In a machine of the character stated, a tool adapted to be vertically guided said tool having a substantially lateral cutting edge and having a guiding face and a recessed portion substantially at right angles 35 to the cutting edge, means for operating the tool, superimposed table parts capable of varied adjustments movable in unison laterally of the machine, one of said table parts being movable transversely of said lateral 40 movement, means for operating said table parts in unison, means for imparting a transverse movement to the last mentioned table part in conjunction with said table operating means and independent means for imparting such a transverse movement independently of the table operating means. 45

In testimony whereof, I have hereunto signed my name.

EMILE J. LUSTER.
